UNITED STATES PATENT OFFICE.

JAMES S. BALDWIN, OF NEWARK, NEW JERSEY.

PORTABLE BELL AND BRACKET SYSTEM.

SPECIFICATION forming part of Letters Patent No. 268,448, dated December 5, 1882.

Application filed February 8, 1881. Renewed October 2, 1882. (No model.)

To all whom it may concern:

Be it known that I, JAMES S. BALDWIN, a citizen of the United States, residing at Newark, in the county of Essex and State of New Jersey, have invented certain new and useful Improvements in Portable Bell and Bracket Systems; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification, and in which—

15 Figure 1 is a perspective of three of the brackets arranged on a line with each other, with the connecting-wires broken, but illustrating a method of connecting the brackets, one of the brackets having the portable bell 20 suspended therefrom; and Fig. 2 is a longitudinal section through one bracket and bell.

25 My invention relates to electric alarm and call bells; and it consists in the system or method in which a portable bell is used in connection with a series of brackets or other suitable instruments having electrical connection one with another, so that the bell can be readily attached and detached or changed from any one of the brackets and an alarm sounded from 30 any point within the circuit, determined by suspending the portable bell from the bracket at the desired point.

35 It also consists in the means and the combination of parts hereinafter described, and sought to be specifically defined by the claims.

I will now describe means by which the bracket and portable bell system may be carried out.

40 In the accompanying drawings, the letter A indicates a bracket, made preferably of hard wood, and provided with a metallic stud, B, a pin, C, and a key, D. The key is slightly curved in the direction of its two ends, so that one end will be free from contact with the pin 45 C, except when pressed against it, and the other end will bear against a portable bell, when suspended from the bracket, so as to hold it against the head of the stud B. Any other construction that will effect the same results 50 will answer. The key is held to its place by

a pin, E, which may have a post, F, formed as part thereof, the pin being screwed through the key into the bracket in such a manner that when the key may turn on it as upon a pivot, so that when the key is turned a pin or screw may be 55 passed through the hole G into the wall or other support for the bracket; but such construction is not essential to the working of the bracket in establishing electrical connections. A bracket is placed in as many rooms or places 60 in the building as is desired, and each one is connected to the other by a wire, H, or branch thereof, which connects with the pin E of each bracket. A battery-wire, I, or branch thereof, passes from the pin C of one bracket to the 65 corresponding pin of another bracket, and a second battery-wire, J, likewise connects the brackets by passing from one stud B to corresponding studs in the other brackets. The two 70 battery-wires, I and J and wire H, which may be run to any points, constitute a circuit, to which, at any desired point, a bracket can be connected, and when a bell is hung upon the bracket it will respond to a touch upon any other bracket. 75

The portable bell, for illustration, may be of any pattern, and consist of two metal plates, K and L, separated and insulated from each other by an intermediate strip, M, of vulcanite or other suitable non-conducting material. 80 The plates K and L are fastened to the wood or other suitable block, N, which may be a part of the frame carrying the striking-gong. A hole to form a loop is cut through the plates K and L and strips M above the connection 85 with the block N, and the plate L about the hole or loop is cut away, so as to expose the strip M and prevent plate L from coming in contact with the stud B when the bell is suspended therefrom. Both plates K and L are 90 connected to the bell or gong by means respectively of wires O and P. The bell is suspended from the stud B of the bracket by passing the loop over the stud. The end of plate L rests upon or bears against the end of key 95 D, and the spring of the latter presses the loop end of the bell, or rather the plate K, against the head of stud B. The plate K is in contact with the stud, but plate L is not, because it is cut away immediately next thereto. 100

Now, to illustrate the operation of the system, we will assume that bracket No. 1 is in one room and bracket No. 3 in another part of the building where the servant of the household may be. The key is suspended from bracket No. 3. The person to call the servant is in room with bracket No. 1. The key of bracket No. 1 is depressed till it touches the pin C. The current which passes along the battery-wire I will now pass through the key into wire H, thence along said wire till it reaches bracket No. 3, then through pin E into key D, from there into plate L of the bell, down the same to the wire O, leading to the gong, striking the alarm, thence through wire P to plate K, from there into stud B, through the same into battery-wire J, and then off to the battery. If the servant should leave one part of the building and go to another part, the bell may be taken from off the last bracket and hung or suspended from the bracket in that part of the building where the servant is engaged for the time, so that when a call is made the alarm will be sounded on the bell, placed by the servant where it can be heard.

Any number of these brackets and bells can be used, and, if desired, the alarm can be sounded in more rooms than one at the same time by suspending bells from the several brackets. The brackets can be placed on door and window frames and the doors and windows connected thereto, so as to make a connection between the wires I and H in the same manner and with like results as by pressure upon the key by hand, as already described.

From the foregoing it will be seen that the wire H is practically a continuation of the battery-wire, and that by pressing any key till it touches the pin C that key and all the others are made the termini of the battery-wire I.

A front-door bell can be connected by wires to the brackets, so that the bell can be made to ring in any part of the building or in several parts at the same time by suspending the portable bells from any one or more of the brackets.

There are other means that may be used to

attract attention besides the alarm-bell—for instance, an unfolding visual signal—so that when the term "bell" is used it will be understood to include other portable means for attracting attention. 50

I do not wish to confine myself to the details of construction hereinbefore given; but,

Having described my invention, what I claim is—

1. A system of electric call-bells herein described, wherein are employed a series of brackets connected to one another by battery-wires and provided with means for establishing a current between the battery-wires, any two or more brackets, and a portable bell, whereby an alarm can be sounded from any bracket at any other bracket in the circuit, determined by suspending the portable bell from the desired bracket where the alarm is to be sounded, substantially as set forth. 65

2. The combination of battery-wires I and J, a wire, H, connecting a series of keys, D, adapted to establish a current between wires H and I, a portable bell adapted, when brought in contact with key D, to transmit the current through the bell, whereby an alarm is sounded, and then off through wire J, substantially as set forth. 70

3. A portable electric bell provided with plates K and L and separating-strip M, and an alarm-gong connected thereto, substantially as set forth. 75

4. The bracket A, provided with key D, pins C and E, stud B, adapted to receive a bell or its equivalent, and connected wires, substantially as set forth. 80

5. The portable bell provided with plates K and L and strip M, in combination with bracket A, provided with key D, pins C and E, stud B, and connecting-wires, substantially as set forth. 85

In testimony whereof I affix my signature in presence of two witnesses.

JAMES S. BALDWIN.
